UNITED STATES PATENT OFFICE.

JOHN F. MAINS, OF INDIANAPOLIS, INDIANA, ASSIGNOR OF THREE-FOURTHS
TO BRUCE CARR, HARVEY M. LA FOLLETTE, AND EDWARD J. ROBISON,
ALL OF SAME PLACE.

MAIL-SACK CRANE.

SPECIFICATION forming part of Letters Patent No. 447,471, dated March 3, 1891.

Application filed July 10, 1890. Serial No. 358,293. (No model.)

To all whom it may concern:

Be it known that I, JOHN F. MAINS, a citizen of the United States, residing at Indianapolis, in the county of Marion and State of 5 Indiana, have invented a new and useful Improvement Mail-Sack Cranes, of which the following is a specification.

My invention relates to an improvement in a mail-sack crane for which my application for 10 a patent, Serial No. 348,861, has been allowed.

The objects of my present improvement are, first, to provide improved means for temporarily securing the mail-sack to the crane, whereby the tearing of the sack or the rings 15 therefrom may be prevented; second, to provide means for catching a mail-sack dropped from a moving train, and, third, to provide a tripping-arm for operating a mail-sack dropper, and means for automatically swinging 20 said arm into and out of the path of a mail-sack dropper mounted on a moving car, all as hereinafter fully described.

The accompanying drawings illustrate my invention.

25 Figure 1 represents a side elevation, showing the outgoing mail-sack in position to be delivered, the net spread for catching the incoming sack, and the arm for tripping the mail-sack dropper extended. Fig. 2 is a front 30 elevation showing the position of the parts after the outgoing sack has been taken from the crane and the incoming sack has been received. Fig. 3 is a view in perspective, on a larger scale, of the improved means for attaching 35 the outgoing sack to the crane.

A is a post, preferably of metal, erected beside the railroad and having a pair of arms B and C pivoted thereto, so as to swing in a vertical plane, and adapted to hold the outgoing 40 mail-sack S extended between them, being in this respect similar to the device shown in my above-mentioned application.

In the device there shown, as in all other mail-sack cranes, so far as I am aware, the 45 vertically-swinging arms, between which the mail-sack is extended, are provided at their outer ends with tips or spurs which enter the rings or loops on the ends of the mail-sack, and are pivoted at one end to the vertically-swinging arms, so as to swing horizontally 50 thereon, so that when the sack is caught by

the catching-fork on the mail car the tips yield laterally to the movement of the sack. It has been found in practice that when the mail-sack is struck by the catching-fork the 55 effect is to bend the sack and thus to shorten the sack. To prevent the tearing of the sack or its connection with its end rings under this strain dependence has heretofore been had on the lateral yielding of tips and the 60 vertical yielding of one or both of the arms; but it is found that the arms do not yield vertically quickly enough to prevent the rings from being torn off, and the tips being designed to swing laterally only on the arms 65 cannot approach each other or the catching-fork, but in swinging laterally tend rather to increase the strain on the sack. For the purpose of avoiding this difficulty each of the vertically-swinging arms B and C is provided 70 on its inner side, near the end, with a hook d, to which a short bar E is attached by means of an eye F, formed in the bar, so that the bar is free to swing both laterally and inward toward the arm. The end of the arm extends beyond the end of the bar E and bends inward to form a rest h for the free end of 75 the bar.

For the purpose of presenting a slight resistance to the lateral movement of the end 80 of bar E the end of the bar is made concave transversely, and the bearing-surface i of the rest h is made correspondingly convex.

In securing the mail-sack S to the arms the 85 rings or loops on the opposite ends of the sack are slipped, respectively, onto the free ends of bars E, which are then engaged with the rests h, thus holding the sack extended in the position shown. When the sack is struck by the catching-fork, the free ends of 90 bars E are first drawn laterally off of their respective rests, and are then free to swing both laterally and vertically toward each other, so that the sack is quickly released and excessive strain is avoided.

95 For the purpose of preventing the rings of the sack from slipping inward along the bars E, I provide in each of the arms B and C a notch j, in which the outer edge of the ring rests.

100 For the purpose of securely catching a mail-sack dropped from a train I pivot to the mast

A, below the arm C, a third arm L, the free end of which is suspended from arm C by a chain *m*. Other chains *n n*, connected by transverse chains *o o*, form a net, which is attached 5 at its ends to the arms C and L. Arms C and L are sustained in a horizontal position, and the net is held open by the mail-sack S. The incoming sack T is caught by the chains, and, the outgoing sack S being at the same time 10 taken away, arms C and L fall, and the chains are drawn over the sack T, so as to envelop it, as shown in Fig. 2.

For the purpose of dropping a sack with the greatest safety from a moving car I have 15 invented a device having a trip-lever for discharging the sack, said lever being operated by coming in contact with a fixed object arranged beside the track. I have filed for said device a separate application for a patent of 20 even date herewith, and I have represented said trip-lever in Fig. 1 of these drawings by the dotted lines *x*.

For the purpose of providing an object for 25 said trip-lever to strike against, which will be automatically placed in the path of the trip-lever by the act of suspending the outgoing sack from the crane, and which will be automatically withdrawn when the outgoing sack is removed, I mount in a bearing R, secured to the mast, a shaft *s*, having at opposite ends duplicate bent arms *t t*. Secured to shaft *s* is an arm *u*, which is connected with the rearward extension of arm B by a link *v*. Arm B is held normally in a vertical position 30 by the counter-weight *y*, and the bent arms *t* are then held out of the path of the trip-lever *x*, as shown in Fig. 2; but when arm B is drawn down to a horizontal position shaft *s* is turned and the arms *t* are turned downward and forward into the position shown in 35 Fig. 1, where they are held so long as bag S is in position. In this position the trip-lever

will strike one of the arms *t* when approaching in either direction.

I claim as my invention—

45

1. In a mail-sack crane having a pair of horizontal arms arranged to hold a mail-sack extended in a vertical position between them, the combination, with one of said arms, of a short bar adapted to enter the ring of a mail-sack and hinged at one end to the arm so as to swing laterally thereon and also vertically toward the sack, said arm extending beyond the free end of said bar and forming a rest therefor, substantially as and for the purpose set forth.

2. In a mail-sack crane, the combination of the arm having hook *d* and convex bearing *h*, and the bar E, having eye F and a concaved free end, all arranged to co-operate substantially as specified.

6c

3. In a mail-sack crane, the combination of the arm adapted to swing in a vertical plane and held in a horizontal position by a mail-sack suspended from the crane, and the flexible net attached at its upper end to said arm and suspended therefrom and attached at its lower end to an arm projecting laterally from the crane-mast, all being arranged to co-operate substantially as set forth, whereby the 70 net is held extended by the mail-sack suspended from the crane and is collapsed when said sack is removed, so as to enfold a sack received therein, as set forth.

65

4. In a mail-sack crane, the combination of the mast, arm B, pivoted thereto, shaft *s*, mounted in a bearing on the mast and having bent arms *t*, arm *u*, and link *v*, all arranged to co-operate substantially as and for the purpose set forth.
